TRAINING DEVICE

Rose P. Gallagher, 1 Valley Brook Road,
Westboro, Mass. 01581

Filed Nov. 10, 1969, Ser. No. 20,028

Term of patent 14 years

Int. Cl. D19—8

U.S. Cl. D25—1

FIG. 1

FIG. 2

FIG. 3

FIG. 1 is an enlarged perspective view of a training device, showing my new design;

FIG. 2 is an elevation of the device as seen if the view in FIG. 1 were rotated 120° on its vertical axis.

FIG. 3 is an elevation view of the device as seen if the view in FIG. 1 were rotated 120° in the direction opposite to that used in FIG. 2.

The bottom of the device is plain and unornamented.

I claim:

The ornamental design for a training device, as shown and described.
